TREMIE PIPE CONSTRUCTION

Mac Silver, San Francisco, Calif.

Application April 28, 1953, Serial No. 351,712

4 Claims. (Cl. 61—63)

This invention relates generally to methods for the pouring of tremie concrete, or other discrete material, and to apparatus for using such methods.

Conventional equipment for the placement of tremie concrete employs a vertical pipe having a hopper at its upper end into which the wet concrete mix is introduced. At the beginning of the pour the lower open end of the pipe is positioned near the bottom of the confined space to be filled, and as the level of the poured concrete rises above the lower end of the pipe, the pipe is gradually elevated while introduction of concrete continues. This method necessitates a continual change in the elevation of the hopper at the upper end of the pipe. Where the depth of the space to be poured is such as to require a tremie pipe of considerable length, which is elevated a comparable amount during the pour, elaborate equipment must be used for elevating and introducing the mix into the hopper. Curtis, 2,562,416 discloses a tremie pipe having provision for detachably securing a hopper at various points along the length of the tremie pipe. Such an arrangement simplifies pouring operations, but likewise involves some vertical movement of the hopper as the pipe is raised, and furthermore it requires a pipe having special side openings to which the hopper can be coupled.

In general it is an object of the present invention to provide a method and apparatus of the above character, making possible the pouring of tremie concrete or other discrete material from a fixed platform, without special means for elevating the mix to different levels.

Another object of the invention is to provide an apparatus and method of the above character making possible the use of a fixed hopper for receiving the concrete mix or other material while permitting continuous elevation of the tremie pipe.

Another object of the invention is to provide a method and an apparatus of the above character which will greatly facilitate the pouring of tremie concrete or other discrete material, and which will require a minimum of interruption to pouring operations.

Additional objects of the invention will appear from the following description in which the preferred embodiment of the invention has been set forth in detail in conjunction with the accompanying drawing.

Referring to the drawing:

Figure 1 is a side view, illustrating apparatus incorporating the present invention.

Figure 2 is a view like Figure 1, but showing the parts in a different operating position.

Figure 3 is a view like Figure 1 and showing the parts in a third operating position.

Figure 4 is a cross sectional view taken along the line 4—4 of Figure 3.

Figure 5 is a cross sectional view taken along the line 5—5 of Figure 4.

The apparatus illustrated in the drawing consists of a vertical pipe 10 which is of sufficient length to extend down to the bottom of the space to be poured. At some

2

convenient elevation above the upper end of the pipe 10 there is a pouring platform 11, and at a level distance below the platform 11, there is a working platform 12. An opening 13 is shown in the platform 12 for accommodating the pipe 10. A hopper 14 is fixed to the platform 11, and receives the concrete mix or other material to be poured.

A considerable length of the pipe 10 consists of the pipe sections 10a, 10b, 10c, 10d, 10e, which are detachably secured together by suitable coupling means 16, such as conventional bolted flanges.

Each pipe section is of a length somewhat less than the distance between the lower end of the hopper 14 and the platform 12. A similar coupling 17 connects the lower discharge end of hopper 14 to the conduit section 18. This conduit section is of a length substantially the same, or slightly less, than the length of the pipe sections 10a—10e, and is illustrated in Figure 1. It slidably and telescopically fits within the uppermost pipe section 10a.

20 Suitable means is provided for supporting and elevating the pipe 10 as the pouring proceeds. For this purpose I have shown a cable 19, which is wound upon the winch 20. The lower end of this cable is attached by a sling 21 to a point along the length of the pipe 10 which is well below the platform 12.

Operation of my apparatus is as follows:

Assuming that the pipe 10 extends to the bottom of the space to be poured, and that the uppermost pipe section 10a is telescopically engaged with the conduit 18, a pour is started by introducing the wet mix into the hopper 14, whereby the concrete flows downwardly through the pipe to be deposited in the space to be filled.

30 As the elevation of the poured concrete rises about the lower end of the pipe, the pipe is elevated by operation of the winch 20, whereby its lower end is maintained at an optimum depth below the level of the poured concrete. When the uppermost pipe section 10a has been fully telescoped over the conduit 18, pouring is temporarily interrupted, while the conduit 18 is being uncoupled from the hopper, and pipe section 10a uncoupled from the next lower section 10b. When these parts have been uncoupled the conduit and top section 10a are removed as a unit (see Figure 2) and then the same or a substitute conduit 18 reapplied to the hopper. Immediately after

40 reapplying the conduit 18 to the hopper 14, the pipe 10 is elevated a small amount to again telescope the conduit 18 with pipe section 10b, and then the pouring proceeds in the same manner as previously described. When pipe section 10b is fully telescoped with the conduit 18, these parts are uncoupled in the same manner as previously described, with the conduit 18 telescoped with the section 10c.

45 It will be evident that by repeating these operations the tremie pipe can be elevated any desired amount while the pouring proceeds without interruption, except for the short interval required to uncouple the conduit and the uppermost pipe section, and for reapplying the same or a like conduit 18 to the hopper.

50 It will be apparent that the apparatus and method described above has many advantages over conventional equipment and methods. No equipment is required to lift the mix to various elevations for introduction into the hopper 14. Because the hopper remains stationary at all times, simple equipment, such as hand carts or a conveyor, can be used for introducing the mix. While

55 pouring is proceeding the tremie pipe can be elevated continuously to maintain the lower end of the pipe at an optimum depth below the level of the poured concrete. The tremie pipe does not require side openings but may be simple pipe sections of conventional construction,

60 coupled together to form a tremie pipe of any desired length.

While the invention has been described as particularly applicable to the pouring of a wet concrete mix, it can be used to advantage for the handling and placement of other discrete materials or mixes, such as sand and the like.

I claim:

1. Apparatus for the placement of tremie concrete or other discrete material comprising a hopper adapted to be carried by a fixed support and serving to receive a concrete mix, a working platform disposed below the hopper, a pipe extending downwardly from the hopper and past the working platform, an upper portion of the pipe comprising a plurality of detachable sections, the length of each section being less than the vertical distance between the upper end of the hopper and the working platform, and a conduit detachably secured to the lower end of the hopper and extending downwardly into telescopic engagement with the uppermost one of said pipe sections, the uppermost pipe section together with said conduit being removable as a unit.

2. Apparatus for the placement of tremie concrete or other discrete material comprising a pouring platform, a hopper fixed with respect to the pouring platform and adapted to receive a concrete mix, a working platform disposed below the pouring platform, a pipe extending downwardly from the hopper and past the working platform, an upper part of the pipe comprising a plurality of detachable pipe sections each of said sections having a length less than the vertical distance between the working platform and the lower end of the hopper, and a conduit detachably secured to the lower discharge end of the hopper and fitted telescopically within the uppermost pipe section, said conduit together with said uppermost pipe section being removable as a unit from the hopper and pipe respectively, thereby enabling raising the pipe into telescopic engagement with another like conduit attached to the hopper.

3. Apparatus for the placement of tremie concrete or other discrete material comprising a pouring platform, a hopper fixed with respect to the pouring platform and

adapted to receive a concrete mix, a working platform disposed below the pouring platform, a pipe extending downwardly from the hopper and past the working platform, an upper part of the pipe comprising a plurality

5 of pipe sections detachably and rigidly secured together at their adjacent ends, each of said sections having a length less than the vertical distance between the working platform and the lower end of the hopper, and a conduit having its upper end detachably and rigidly secured to 10 the lower discharge end of the hopper and fitted telescopically within the upper pipe section, said conduit together with said upper pipe section being removable as a unit from the hopper and pipe respectively, thereby enabling raising the pipe into telescopic engagement with 15 another like conduit attached to the hopper.

4. A method for the pouring of tremie concrete or other discrete material characterized by the use of apparatus as defined in claim 1; comprising continually introducing a concrete mix into the hopper whereby the mix

20 flows down through the pipe for discharge at the lower end thereof, continually raising the pipe while the pouring proceeds, whereby said conduit gradually telescopes into the uppermost section of the pipe, interrupting introduction of the mix into the hopper when the conduit is

25 substantially completely telescoped within the uppermost section, removing the conduit from the hopper and the uppermost pipe section from the remainder of the piping, applying another conduit to the hopper, elevating the pipe whereby the next pipe section is brought into telescopic engagement with the conduit, and then continuing 30 the introduction of concrete mix into the hopper with further continual elevation of the pipe as the pouring proceeds.
